UNITED STATES PATENT OFFICE.

HARRISON HOWELL, OF SULLIVANVILLE, NEW YORK, ASSIGNOR TO ABRAM BALES AND ISAAC HOWELL, OF SAME PLACE.

CLOTHES-POUNDER.

SPECIFICATION forming part of Letters Patent No. 223,647, dated January 20, 1880.

Application filed November 15, 1879.

To all whom it may concern:

Be it known that I, HARRISON HOWELL, of Sullivanville, in the county of Chemung and State of New York, have invented certain new and useful Improvements in Clothes-Pounders; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a perspective of my clothes-pounder, and Fig. 2 is a longitudinal sectional view of the same.

My present invention relates to an improved clothes-pounder constructed substantially as herein set forth and claimed.

In the drawings, A designates a wooden handle about four feet long; and B, an enlarged extension of the same, which forms a central piece or plate of the base of the pounder.

C designates four plates, which are secured by screws to the four sides of the central plate, B. At the juncture of this plate or enlarged extension part and the handle are shoulders

b, so that when in place the upper outer edges of the plate C will be flush with the exterior of the handle. The plates C flare outwardly at the base of the pounder, as shown, and 30 openings d are formed at the four corners, for the passage of water and air while the pounder is forced upon the clothes.

By placing the clothes within a tub of water and using this pounder, they will be raised, 35 turned, pounded, and thoroughly washed.

What I claim, and desire to secure by Letters Patent, is—

A clothes-pounder constructed with the handle A, enlarged extension B, shoulders b, and 40 the plates C, secured to the sides of the extension part B, and flaring outwardly at the base of the pounder, with the four corner openings d between them, substantially as herein shown and specified.

In testimony that I claim the above I have hereunto subscribed my name in the presence of two witnesses.

HARRISON HOWELL.
